UNITED STATES PATENT OFFICE.

GILBERT A. LIESER, OF BEAVER DAM, WISCONSIN, ASSIGNOR TO MALLEABLE IRON RANGE COMPANY, OF BEAVER DAM, WISCONSIN, A CORPORATION OF WISCONSIN.

COMBINATION RANGE.

Application filed December 31, 1921. Serial No. 526,155.

To all whom it may concern:

Be it known that I, GILBERT A. LIESER, a citizen of the United States, residing at Beaver Dam, in the county of Dodge and 5 State of Wisconsin, have invented certain new and useful Improvements in Combination Ranges, of which the following is a specification.

This invention relates to a cooking range

10 which combines in a single structure the features of a gas range and a coal range, so that either form of fuel may be used as occasion may warrant. The object of the invention is to so arrange the various portions of the 15 range that the same will be compact and convenient in structure and adapted to utilize either form of fuel with a minimum waste of heat efficiency. The range furthermore is designed with a view to economy in 20 the utilization of floor space, so that the combined range of the present invention occupies no greater area of floor space than that occupied by a coal range of standard construction.

25 Further details will appear from a description of the invention which consists in the features of construction and combination of parts hereinafter described and claimed.

30 The drawing shows a perspective view of the front of the range.

The combined range comprises a coal burner section A, a gas oven and broiler section B, and a gas top C arranged as indicated in the drawing, that is to say, the coal section constitutes the base or body of the structure, the combined gas oven and broiler constitutes a superstructure arranged as shown to rest upon the top of the coal section 40 at the right hand thereof and the gas top C constitutes an extension projecting toward the left without floor contact, which arrangement is entirely feasible by reason of the fact that the preponderance of weight 45 is carried by the opposite end of the structure. The relative right and left hand positions shown may obviously be reversed although the arrangement indicated is generally preferred as constituting a more convenient location for the respective sections.

The coal section separately considered constitutes a coal range of standard construction comprising a fire box 1, an ash pit 2, an oven 3, and a cooking top 4, the latter 55 being located directly above the fire box.

Since the present invention is directed primarily to the arrangement and location of the several portions of the structure into a unitary or organized entity, and since the individual separately considered parts are 60 of standard formation and may be modified as to detail, it is not deemed necessary to submit a specific description of each of these details.

The superstructure B comprises a gas 65 oven 5, a gas broiler 6 and a gas burner pipe 7 which supplies the burners intermediate the gas oven and broiler. The superstructure, as shown, is of substantially equal height and depth with the coal range section 70 but of lesser width which exposes the coal cooking top 4, which is provided with the usual removable cover plates 8, which cooking top lies flush with the gas top extension C, so that abundant level space is afforded 75 on these two tops, which constitutes an extension the one of the other, for the manipulation of cooking utensils. The gas cooking top is provided with the usual burners 9 which are supplied by the same gas pipe 7 80 which furnishes gas to the superstructure.

The gas top extension is supported upon a bracket 10 which projects laterally from the coal range section and a back plate 11 and shelf 12 are provided which furnish a 85 combined backing for the cooking tops and serve to knit together the structure into an integral unit.

From the foregoing description it will be noted that the present combined structure 90 possesses all of the individual advantages of a coal range and a gas range with additional features of advantage resulting from the combination of the two structures. By locating the gas superstructure immediately 95 above the coal oven, the coal range structure serves as a base or support for the gas burning superstructure, so that the space, not otherwise available, is utilized without extending the floor area of the combination. 100 At the same time by arranging the cooking tops in alignment with one another, an unbroken top area is afforded for the manipulation of cooking utensils, the area provided by the gas top extension, fully compensating 105 for the space occupied by the gas burning superstructure. Furthermore, by arranging the superstructure in the manner indicated, ample provision is made for extending the gas top without floor support so that the 110

underlying floor space is available for other purposes and the absence of floor supports at this point makes it easy to clean the floor or to utilize the floor space for storage purposes. The arrangement is one which materially reduces the apparent size of the structure as a whole so that it presents a much more slight and attractive appearance than would be the case if the gas burning features were carried down substantially to the floor level.

Furthermore, on occasion it may be found desirable to utilize both the coal burning and gas burning features of the combined structure, either to increase the cooking capacity or as a matter of temporary convenience or for special purposes, and in such case, the heat generated by the coal burning portion of the combination structure will in a large measure be available for the heating of the burning superstructure, which heat thus available would under ordinary circumstances, be wasted in large measure.

The arrangement is one which is extremely convenient in the point of location of the various cooking sections, and at the same time is one which combines strength, durability and compactness of structure with attractiveness in appearance. Although the lower section has been defined as a coal burner range section, it is intended that the term "coal" should apply to the use of wood, briquettes, or other like fuel commonly used as a substitute for coal, and in like manner the term "gas" should be construed to include gasoline or like fluids commonly used as a substitute for gas.

I claim:

1. In a combined cooking range, the combination of a coal burning section constituting the base of the structure and designed exclusively for the burning of coal and having a coal heated oven at one side thereof, a gas burning superstructure of less width than the coal burning section and superimposed upon the latter above the oven thereof in position to leave exposed a portion of the coal burning section, to constitute a cooking top therefor, the gas burning superstructure being divided into a lower broiling section and an upper oven section and provided with a gas burner intermediate the oven and the broiler, and a gas burning cooking top constituting an extension from the coal cooking top and on the same plane therewith, substantially as described.

2. In a combined cooking range, the combination of a coal burning section constituting the base of the structure and designed exclusively for the burning of coal and having a coal heated oven at one side thereof, a gas burning superstructure of less width than the coal burning section and superimposed upon the latter above the oven thereof in position to leave exposed a portion of the coal burning section, to constitute a cooking top therefor, the gas burning superstructure being divided into a lower broiling section and an upper oven section and provided with a gas burner intermediate the oven and the broiler, and a gas burning cooking top constituting an extension from the coal cooking top and on the same plane therewith, said gas burning extension being wholly supported from the coal burning section without direct floor support and being designed exclusively for the burning of gas, substantially as described.

3. In a combined cooking range the combination of a coal burning section constituting the base of the structure and designed exclusively for the burning of coal and having a coal heated oven at one side thereof, a gas burning superstructure superimposed upon the coal burning section above the oven in position to leave exposed a portion of the coal burning section to constitute a cooking top therefor, a gas burner for heating the gas burning superstructure, and a gas burning cooking top constituting an extension from the coal cooking top and on the same plane therewith, substantially as described.

4. In a combined cooking range the combination of a coal burning section constituting the base of the structure and designed exclusively for the burning of coal and having a coal heated oven at one side thereof, a gas burning superstructure superimposed upon the coal burning section above the oven in position to leave exposed a portion of the coal burning section to constitute a cooking top therefor, a gas burner for heating the gas burning superstructure, and a gas burning cooking top constituting an extension from the coal cooking top and on the same plane therewith, said gas burning extension being wholly supported from the coal burning section without direct floor support and being designed exclusively for the burning of gas, substantially as described.

GILBERT A. LIESER.
